CHRISTIAN WILHELM PAUL HEYLANDT, OF BERLIN-LANKWITZ, GERMANY

PROCESS OF TRANSFERRING LIQUEFIED GASES FROM ONE CONTAINER TO ANOTHER

Application filed March 8, 1929, Serial No. 345,259, and in Germany March 2, 1928.

In transferring liquefied gases of low-boiling point from one vessel to another, and particularly when large quantities of such gases were involved, it has been the practice 5 heretofore to permit pressure to develop automatically from the natural evaporation of the gas in a closed vessel, in order to effect a sufficiently quick transfer of the liquefied gas. Under that method, however, considerable losses by evaporation occurred during the transfer of the gas into the second container. I have found that such losses can be reduced to one fourth if the gas is continuously maintained during storing and transportation at practically ordinary boiling temperature, and at the time of making the transfer, an artificial pressure gas is introduced into the first container for a definite length of time. This can be effected from 20 an outside source, for instance by the use of compressed gas, or by the rapid evaporation of a part of the gas to be transferred or of another liquid gas, and conducting the pressure vapors to the liquid. The liquid will 25 then run out of the containers to be emptied at increased speed, without any substantial evaporation losses taking place.

Tests have shown that especially during the transfer of pressureless liquefied gases 30 into pressure-developing containers, the losses which heretofore have amounted to from 2 to 4 per cent can be reduced by the present method to 0.5 to 1 per cent.

However, also in other respects does the 35 present method offer advantages, inasmuch as the transportation containers for liquefied gases now in use, the discharge openings of which containers, for practical reasons, are usually higher than the lowest liquid level, can be maintained in use, without pressure, and then, during the periods of rest, the pressure difference for the gas stored within the 40 container is increased so that, during rest periods, no gas is lost from such transportation containers, while, when operating the vehicle, the increased gas pressure is immediately 45 again reduced by utilizing the same in the motor so that the liquid to be transferred in 50 accordance with the above-mentioned method

again assumes the temperature of the boiling point. In order to carry out the process, it is advisable to transfer a small quantity of the liquid gas into an evaporator coil, the evaporation products of which, with increased pressure, are led to the vapor or steam chamber of the receptacle which contains the liquid to be emptied. 55

The drawing accompanying this specification 60 illustrates diagrammatically an apparatus suitable for carrying out the present process.

In said drawing, 1 designates the inner container of a liquid tank having a filling 65 pipe 3, said tank being mounted on a truck for transportation. At 2 this pipe 3 is tapped so that, as required, a small quantity of the liquid contents can be drawn off into a coil 4, where it will evaporate. The coil dis- 70 charges into the space above the liquid level, in the container 1, and the pressure gas developing from the drawn-off quantity of liquid is sufficient for the expulsion of the desired liquid to be transferred. The transfer neck 75 of the tank communicates in the well known manner by means of a flexible tube with the transfer vessel 5, which receives the liquid to be brought to pressure gasification by way of self-compression. The tapping tube, of 80 course, is provided with a suitable valve for controlling the flow of liquefied gas to the coil 4.

Having thus described and ascertained the nature of my said invention, what I claim 85 is:

1. The process of transferring liquefied gases from one container to another, which consists in maintaining the liquefied gases at their ordinary boiling temperatures in the 90 first container, and utilizing a portion of the liquefied gases from the first container to apply an artificially increased momentary pressure to the liquefied gases thereby to cause the same to flow at increased speed into an- 95 other container.

2. The process of transferring liquefied gases from one container to another, which consists in maintaining the gases at their ordinary boiling temperatures in the first con- 100

tainer, extracting a small quantity of said liquefied gases from said container and evaporating the same, and returning the vapors to said first container thereby to exert pressure on the liquefied gases and cause the same to flow at increased speed into another container.

3. An apparatus for transferring liquefied gases from one container to another, comprising a vessel having a filler tube, a coil disposed outside of said vessel and adapted to communicate at one end with said tube, the opposite end of said coil being in communication with said vessel above the liquid level, thereby to produce an excess pressure for discharging the liquid from said vessel.

4. An apparatus for transferring liquefied gases from one container to another, comprising a vessel having a filler tube, a coil disposed outside of said vessel and adapted to communicate at one end with said tube, the opposite end of said coil being in communication with said vessel above the liquid level, thereby to produce an excess pressure for discharging the liquid from said vessel, and detachable means for placing said vessel in communication with a second vessel.

In testimony whereof I have signed my name to this specification.
